(57) CLAIM

The ornamental design for a bra including storage pockets, as shown and described.

DESCRIPTION

FIG. 1 is a front, right side perspective view of the bra including storage pocket according to my present invention, shown in the closed condition;

FIG. 2 is a front, left side perspective view thereof;

FIG. 3 is a front elevational view, shown in the opened condition;

FIG. 4 is a right side elevational view thereof; and,

FIG. 5 is a left elevational view thereof.

The broken lines shown in the drawings are for illustrative purposes only and form no part of the claimed design.
